BUILDING UNIT

Erle T. Putnam, Detroit, Mich., assignor to Libbey-Owens-Ford Glass Company, Toledo, Ohio, a corporation of Ohio

Application November 29, 1940, Serial No. 367,732

4 Claims. (Cl. 72—35)

The present invention relates broadly to structural building units and more particularly to composite building blocks for use in the construction of exterior walls.

The composite building block herein provided comprises a body portion or member formed from a cementitious material such as concrete, Haydite, or the like, and an ornamental facing thereto formed of opaque structural glass. The ornamental facing is secured to the body portion of the block by an interposed layer of adhesive material such as asphaltic mastic cement and also by mechanical fastening means in the form of metal holders arranged at the edges of the block and engaging both the ornamental facing and the body portion. In constructing a wall, the blocks are laid up in courses in substantially the same manner as cut stone, granite, or terra cotta. Such a composite building block is now being manufactured and sold commercially by the company to which this application is assigned under the trade name "Glastone," and therefore throughout the application the word "Glastone" will be understood to designate a composite building block of this character.

When forming the exterior walls of buildings of Glastone blocks, the blocks of the lower row or course may either be set at the level of the sidewalk or below the sidewalk line as preferred. However, when the blocks are set below the sidewalk line, precautions must be taken so that the concrete forming the sidewalk is not poured directly against the face of the Glastone.

Although a preferred method of installation of Glastone blocks is recommended by the assignee company, it has been found that in some instances the concrete sidewalk is laid in such a way that upon expansion thereof, the glass facings of the blocks are broken. The cracks thus caused in the glass facing are sometimes confined to the lower portion of the block but, in other cases, they may extend vertically a substantial distance if not throughout the entire height of the block, resulting in an unsightly appearance. Inasmuch as the Glastone blocks used are ordinarily quite large and since only a few inches thereof project below the sidewalk line, it will be seen that any cracks caused in the glass facing may extend upwardly above the pavement a sufficient distance to be quite noticeable to passers-by and thereby detract from the appearance of the installation.

It is the aim of this invention to provide an improved Glastone type of block which is particularly adapted for use in the construction of the

bottom rows or courses of the exterior walls of buildings and especially where the blocks are to be set below the sidewalk line. According to the invention, the ornamental glass facing of the block is of a novel construction and arrangement so that even though the facing is broken by expansion of the sidewalk, the vertical or upward travel of the resulting crack or cracks formed therein will be definitely limited and confined to a relatively small area at the bottom of the block. This is accomplished by providing along the bottom marginal portion of the block a separate relatively narrow strip of glass which projects only a relatively short distance above the sidewalk level. In this way, if the glass facing should be broken by expansion of the sidewalk, any crack or cracks which develop in the facing will be confined to the relatively narrow strip of glass at the bottom of the block and will be prevented from passing upwardly into the major or body portion of the glass facing.

Other objects and advantages of the invention will become more apparent during the course of the following description, when taken in connection with the accompanying drawing.

In the drawing, wherein like numerals are employed to designate like parts throughout the same:

Fig. 1 is a front elevation illustrating a portion of an exterior building wall embodying in its construction composite blocks provided by the present invention;

Fig. 2 is a vertical section taken substantially on line 2—2 of Fig. 1; and

Fig. 3 is a front view of one of the blocks showing particularly the ornamental glass facing and metal holders associated therewith, the facing being partially broken away.

With reference now to the drawing and particularly to Fig. 1, there is illustrated a portion of the exterior wall of a building provided with a glazed opening 5 in which is mounted a pane of glass 6 supported in the window opening by the metal sash construction 7 arranged at the top, bottom, and sides of said window. The exterior wall of the building is constructed of or faced with the Glastone blocks 8 set one upon the other in a series of horizontal rows or courses. The bottom row or course of blocks 8 may be set at the level A of the sidewalk B, but in many cases the blocks are set slightly below the sidewalk line as indicated by the broken lines in Fig. 1 and by the full lines in Fig. 2.

Each of the blocks 8 is of a composite construction comprising a body portion or member

9 preferably formed from a cementitious material such as concrete, Haydite, or the like, and an ornamental facing 10 preferably of opaque structural glass. The glass facing 10 covers substantially the entire front surface of the body portion 9, and interposed between said facing and body portion is a relatively thick, substantially uniform layer of adhesive material 11, preferably an asphaltic mastic cement, which serves not only to bind the facing to the body portion but also permits relative expansion and contraction between the two without danger of the facing becoming broken or accidentally displaced. The layer of mastic 11 also serves to cushion the glass facing against shock and blows, thereby increasing its resistance to breakage.

Arranged at each edge of the glass facing 10 is a metal holder 12, and these holders cooperate to form a frame extending entirely around the perimeter of the block for mechanically securing the facing to the body portion. Each of the metal holders 12 comprises a longitudinally extending channel portion 13 which is received between the body portion 9 and facing 10 of the block for spacing them from one another as shown in Fig. 2. The outer wall of the channeled portion 13 constitutes a shoulder which abuts the rear surface of the glass facing 10 and extending forwardly therefrom and at substantially right angles thereto is a flange 14 disposed opposite the respective edge of the facing and terminating in an inwardly directed lip 15.

The peripheral edges of the glass facing are preferably square with the opposite surfaces thereof and engaging said edges are strips 16 of suitable resilient cushioning material such as asphaltic impregnated cork, although they may be of rubber, rubber composition, etc. These cushioning strips 16 serve to protect the edges of the facing and also act to prevent chipping or spalling of the facing during the setting of the block in a wall.

As shown in Fig. 2, the cushioning strips 16 terminate inwardly of the outer surface of the facing 10 and also that the flanges 14 and lips 15 of the metal holders cooperate with the outer walls of the channeled portions 13 to define substantially U-shaped channels in which said strips are received. The cushioning strips 16 may or may not be secured to the edges of the facing, as desired, and they are preferably relatively thicker than the width of the lips 15, so that while the lips extend over or overlap the forward edges of the strips, they do not contact with the edges of the facing.

The inner wall of the channeled portion 13 of each metal holder 12 constitutes a shoulder which engages the outer surface of the body portion 9, said shoulder projecting slightly beyond the flange 14 and extending at substantially right angles with respect thereto is a relatively wide, flat, load-bearing surface 17 which is disposed opposite the body portion of the block. Formed integral with and constituting a continuation of the load-bearing surface 17 is an inwardly directed flange 18 which is embedded in the body portion 9.

In building a wall, the blocks 8 are laid up one upon the other in courses to form a plurality of vertical and horizontal rows. Due to the fact that the load-bearing surfaces 17 of the metal holders 12 project beyond the edges of the glass facing, there will be formed around the edges of the body portion 9 a continuous load-bearing ledge 19 which also projects slightly beyond the

edges of the facing. As a result, when the blocks are laid up in courses in a wall with the load-bearing surfaces 17 of vertically adjacent blocks in engagement with one another, the adjacent

5 glass facings 10 will be spaced slightly from one another and in this space is adapted to be inserted a suitable pointing or caulking material 20. This pointing material may be applied by means of a spray gun and will ordinarily fill the 10 mating channeled portions 13 of adjacent metal holders.

When the blocks 8 are mounted in place, the body portions 9 of vertically adjacent blocks will also be spaced from one another inwardly of the 15 load-bearing surfaces 17, and this space can be filled with a layer of mortar 21. With such a construction, the structural load of the wall will be supported entirely by the body portions 9 of the blocks with none of the load being placed upon the glass facings 10. In other words, the load of one block is transferred directly to the body portion of the next lower block and each block takes the full strain of the blocks above it. Since it is impossible for the vertically adjacent glass facings to engage one another when the blocks are set in place in this manner, strain upon the facings will be reduced to a minimum, thereby eliminating breakage and chipping thereof.

When the blocks 8 are to be used above the level of the sidewalk, the glass facing 10 may consist of a single relatively large sheet or plate of glass covering the entire front surface of the body portion 9. However, it has been found that when the blocks are set below the level A of the concrete sidewalk B as shown in Fig. 2, there is sometimes a tendency for the glass facing to be broken upon expansion of the sidewalk, and this is particularly true if the concrete is poured directly against the glass facing. When this occurs, if the glass facing is formed of a single large sheet or plate of glass any crack or cracks which might be caused therein are apt to travel vertically throughout the entire height of the block or at least a major portion thereof, with the result that such crack or cracks will be quite noticeable to passersby and render the blocks themselves unsightly as well as detract from the appearance of the wall. This is especially true when the blocks of the bottom row are relatively large and project a considerable distance above the sidewalk level.

As brought out above, the primary object of this invention is to provide a building block having an ornamental glass facing of novel construction and arrangement so that even though the facing be broken by expansion of the sidewalk any crack or cracks which might develop in the facing will be restricted to and definitely confined within a relatively small area of the facing adjacent the bottom of the block. To this end, the glass facing 10 is formed of two pieces or sections of glass which cooperate to cover substantially the entire front surface of the body portion 9 of the block. More particularly, the facing 10 comprises a relatively large sheet or plate of opaque structural glass 22 covering the entire front surface of the body portion 9 of the block with the exception of a relatively narrow marginal portion along the bottom thereof which is covered by a separate relatively narrow strip of glass 23. The glass strip 23 is preferably only a few inches in width and, as shown in Fig. 2, is adapted to be partially set below the level A of the sidewalk B. The glass strip 23 is also prefer-

ably spaced from the glass sheet or plate 22 and interposed therebetween is a strip or the like 24 of suitable cushioning material. The cushioning material 24 preferably terminates inwardly of the outer surfaces of the glass plate 22 and glass strip 23 to provide a joint which is filled with a suitable pointing or caulking material 25.

By forming the glass facing 10 in this way, it will be readily seen that should the glass strip 23 be broken for one reason or another, such as upon expansion of the sidewalk B, any crack or cracks which may develop therein can travel upwardly only to the top edge of the strip and will be effectually prevented from extending into the large sheet or plate 22 of the facing. The upward travel of any crack or cracks is therefore definitely limited and such crack or cracks are confined to the glass strip 23. Since this strip is preferably quite narrow, only a small portion thereof will be exposed above the sidewalk line and, in consequence, any crack or cracks which may be caused therein will be restricted to this area of the facing. Thus, the cracks will be quite a distance below the normal eye level so that they will be hardly noticeable to passersby.

By way of example only and as illustrative of the present invention, it might be well to point out that the average size of Glastone bulkhead blocks used is between 5 and 6 square feet and that most of these blocks vary from 18 inches to 24 inches in height. The separate glass strip 23 at the bottom of the block is preferably so designed as to project about 2 inches above the sidewalk line. As the bulkhead block is also preferably set about 2 inches below the sidewalk line, this means that the separate glass strip 23 should be about 4 inches wide.

It is to be understood that the form of the invention herewith shown and described is to be taken as the preferred embodiment of the same, and that various changes in the shape, size and arrangement of parts may be resorted to without departing from the spirit of the invention or the scope of the subjoined claims.

I claim:

1. In an exterior wall construction, a plurality of blocks arranged to form a horizontal row set partially below the sidewalk line and each block comprising a body member, a glass facing therefor including a glass plate covering the entire front surface of said body member with the exception of a relatively narrow marginal portion along the bottom thereof and a separate strip of glass arranged beneath said glass plate and covering the bottom marginal portion of said body member, said separate glass strip being disposed partially beneath the sidewalk line and

partially above said sidewalk line, and means securing said ornamental facing to said body member.

2. In an exterior wall construction, a plurality of blocks arranged to form a horizontal row set partially below the sidewalk line and each block comprising a body member, a glass facing therefor including a glass plate covering the entire front surface of said body member with the exception of a relatively narrow marginal portion along the bottom thereof and a separate strip of glass arranged beneath said glass plate and covering the bottom marginal portion of said body member, said glass strip being spaced from said glass plate and being disposed partially beneath the sidewalk line and partially above said sidewalk line, means securing said ornamental facing to said body member, and cushioning material interposed between the said strip and plate.

3. In an exterior wall construction, a plurality of blocks arranged to form a horizontal row set partially below the sidewalk line and each block comprising a body member, a glass facing therefor including a glass plate covering the entire front surface of said body member with the exception of a relatively narrow marginal portion along the bottom thereof and a separate strip of glass arranged beneath said glass plate and covering the bottom marginal portion of said body member, said separate glass strip being disposed partially beneath the sidewalk line and partially above said sidewalk line, and metal holders at the edges of the block cooperating to form a frame surrounding the ornamental facing and each having a portion engaging said body member and another portion engaging said facing.

4. In an exterior wall construction, a plurality of blocks arranged to form a horizontal row set partially below the sidewalk line and each block comprising a body member, a glass facing therefor including a glass plate covering the entire front surface of said body member with the exception of a relatively narrow marginal portion along the bottom thereof and a separate strip of glass arranged beneath said glass plate and covering the bottom marginal portion of said body member, said glass strip being spaced from said glass plate and disposed partially beneath the sidewalk line and partially above said sidewalk line, a strip of cushioning material disposed between the said strip and plate, and metal holders at the edges of the block cooperating to form a frame surrounding the ornamental facing and each having a portion engaging said body member and another portion engaging said facing.

ERLE T. PUTNAM.
